UNITED STATES PATENT OFFICE.

JOHN W. CHAMPION, OF OSAGE, IOWA, AND OLE BERGE, OF MINNEAPOLIS, MINNESOTA.

HAIR-CURLER.

1,233,185.

Specification of Letters Patent. Patented July 10, 1917.

Application filed February 21, 1917. Serial No. 150,046.

To all whom it may concern:

Be it known that we, JOHN W. CHAMPION and OLE BERGE, citizens of the United States, and residents of Osage, in the county of 5 Mitchell and State of Iowa, and of Minneapolis, in the county of Hennepin and State of Minnesota, respectively, have invented a certain new and useful Improvement in Hair-Curlers, of which the following is a 10 specification.

Our present invention relates generally to hair curlers, and more particularly to a simple, inexpensive curler formed of a single piece of wire, our object being to provide a curler of this type which will be effective and efficient in use for the purpose of curling or crimping the hair, which may be readily manipulated in use, and which will be strong and durable.

20 In the accompanying drawing illustrating our present invention:

Figure 1 is a plan view illustrating the practical application of our improved curler;

25 Fig. 2 is a side view, partly broken away and in section;

Fig. 3 is a perspective view of one end portion of the curler, and

Fig. 4 is a cross section taken substantially on line 4—4 of Fig. 1.

Referring now to these figures, our invention contemplates the bending of a single piece of wire of suitable gage and strength, to form a substantially triangular body having the elongated side portions 10 and 11, as seen in Fig. 1, the cross bar at the base of the triangle being bent inwardly as indicated at 12, forming a catch or hook extending between the spaced-apart ends of 35 the elongated sides 10 and 11.

The side portion 11 of the body terminates at the apex of the triangle, its extremity appearing at 13 as seen particularly in Fig. 4, and the end of the side portion 10 is looped 40 around the side portion 11 at the apex of the triangular body, and adjacent the extrem-

ity 13 thereof, as seen at 14 in Fig. 3, so as to thus join the side portions and complete the body of the curler.

The side portion 10 is further provided 50 with an extension bent angularly and upwardly as at 15, over the lateral loop 14, which extension projects centrally between the elongated sides 10 and 11 to form a center pin, and has its free end bent as at 55 16 in Fig. 2, for engagement with the hook or catch 12 before described.

Thus, the bending of the extension as at 15 upwardly over the loop 14, provides for sufficient spring in the center pin 16, as to 60 hold the free end 17 thereof engaged with the hook or catch, particularly when the curler is in operation.

In the use of the curler, the hair should be first twisted and then with the center pin 65 16 disengaged and in open position, the hair should be wrapped about the body, including the elongated sides 10 and 11, in the manner shown in Fig. 1, beginning at the narrow end or apex of the body, the center 70 pin 16 being pressed down upon the wound hair and the bent free end 17 engaged with the hook or catch in order to thereafter hold the hair in wound position until it is desired to release the same.

It is obvious that our invention as thus formed will be simple and inexpensive, is capable of effective and efficient use for the purposes stated, and will be strong and durable.

We claim:

1. A hair curler consisting of a single piece of wire bent to form a triangular body portion around which hair may be wound, having its base bent inwardly at an intermediate point, to form a catch, and having elongated side portions, one of which is looped laterally around the other at the apex of the triangular body, and provided with an extension bent angularly and upwardly 85 over the said loop and projecting in the direction of the length of the body between 90

the said sides to form a center pin having its free end bent for engagement with the said catch.

2. A hair curler consisting of a single piece of wire bent to form a triangular body portion around which hair may be wound, having a catch at its enlarged end, and provided with elongated side portions, one of which is looped laterally around the other at the apex of the triangular body to connect the side portions, and is provided with an extension bent angularly and upwardly over the said loop and forming a center pin

projecting in the direction of the length of the body between the said side portions 15 thereof and having its free end engageable with the said catch.

JOHN W. CHAMPION.
OLE BERGE.
